GARAGE CONSTRUCTION

Application filed May 31, 1928. Serial No. 281,659.

This invention relates to multi-story structures for the housing of motor vehicles, in which a system of ramps is used to permit the vehicles to travel from floor to floor under their own power.

In similar structures of the usual type using a system of straight inclined ramps for passing from floor to floor, the intersection of the plane of the ramp with the plane 10 of the floor occurs where the car is turning from the ramp onto the level floor, or vice-versa. In other words, the car is turning in a curve at the same time that it is changing from one plane to the other. As a result in 15 certain positions, the inside wheels or those toward the axes of rotation, are momentarily at a higher elevation than the outside wheels, whereas the latter should be suitably elevated above the inside wheels to compensate for the 20 over-turning tendency due to centrifugal force. This inclination of the car in the wrong direction may be termed negative or reversed banking, and results in a racking or twisting action of the car as well as a feeling 25 of discomfort if the turn is made at an appreciable speed. The same undesirable condition maintains, though in a lesser degree, in certain other positions in which there is a slight inclination of the car toward the axis 30 of rotation, but the inclination continues through only a portion of the turn. The condition is still further aggravated if the change is abrupt from the grade of the ramp to the position of horizontal travel, or vice-versa; that is, if the change of grade is not effected 35 gradually through the medium of a vertical easement curve.

The distance that the car travels in passing from floor to floor is of prime importance, 40 and it is obvious that if the turn can be made while the car is on the grade, this travel distance will be materially shortened.

In structures heretofore built, as far as I 45 am aware, attention has been devoted exclusively to the problem of getting vehicles from floor to floor, and to the permissible maximum grades, and little if any thought has been given to the necessity or desirability of providing a travel path that is easy and 50 comfortable to drive and that eliminates ill

effects on the vehicle and its component parts.

The principal object of this invention is to provide a structure of the type described, in which the ramp system is so designed as to provide an easy and natural movement of a 55 vehicle in traversing the same.

Another object is to provide a structure of the class described, in which the ramps will consume a minimum of floor space, and in which the vehicles traveling the ramps from 60 floor to floor will travel a minimum of distance in passing from floor to floor, while at the same time the grades are kept within very reasonable limits.

Another object is to provide a structure of 65 the class described including two series of oppositely inclined ramps extending between the various floors of the structure, alternate ramps of each series being solely devoted to either up or down traffic. 70

Another object is to provide a structure of the class described comprising two series of oppositely inclined ramp structures, the end portions of each ramp of each series being curved in the direction of the cooperating 75 ramp of the opposite series and banked downwardly towards the axes of the path of travel thereon.

Another object is to provide a structure of the class described provided with two series 80 of oppositely inclined ramps, each ramp of which comprises a relatively straight portion and inwardly curved end portions, the curved end portions being connected together by a cooperating path, and the curved end portions and the cooperating path being banked from a minimum near the junction of the curved and the straight portions of the ramps 85 to a maximum at some intermediate point.

Another object is to provide a structure as 90 above described in which curved paths are provided adjacent the curved ends of a ramp and leading therefrom to the levels of the two floors which the ramp joins in a direction leading away from the path of travel on the 95 corresponding curved ends of the ramp, these curved paths being banked downwardly towards the respective axes of travel so that the outer edges are at a superelevation to the inner edges until the floor levels are reached. 100

Another object is to provide, in a structure of the class described, a path of travel which will facilitate the travel of vehicles thereon with a maximum degree of safety and speed.

5 A further object is to provide, in a structure of the class described, a system of ramps so designed that any floor may be extended in any direction beyond the ramp unit and ready access to the travel paths of the ramps 10 be maintained.

10 The above being among the objects of the present invention the same consists in certain features of construction and combinations of parts to be hereinafter described with reference to the accompanying drawings, and 15 then claimed, having the above and other objects in view.

15 In the accompanying drawings which illustrate suitable embodiments of the present invention and in which like numerals refer to 20 like parts throughout the several different views,—

25 Fig. 1 is a more or less fragmentary diagrammatic sectional side elevation of a structure of the class described illustrating the two series of oppositely extending ramps with which the structure is provided.

30 Fig. 2 is a more or less diagrammatic broken plan view taken through a structure of the class described, certain floors thereof being broken away to better illustrate the present invention.

35 Fig. 3 is a vertical sectional view taken on the line 3—3 of Fig. 2.

40 Fig. 4 is a more or less diagrammatic developed vertical section taken through the center of the path of travel of the ramps shown in Fig. 2.

45 Fig. 5 is a sectional view taken on the line 5—5 of Fig. 2.

50 Fig. 6 is a sectional view taken on the line 6—6 of Fig. 2.

55 Fig. 7 is a sectional view taken on the line 7—7 of Fig. 2.

60 Fig. 8 is a sectional view taken on the line 8—8 of Fig. 2.

65 Fig. 9 is a sectional view taken on the line 9—9 of Fig. 2.

70 Fig. 10 is a sectional view taken on the line 10—10 of Fig. 2.

75 Fig. 11 is a sectional view taken on the line 11—11 of Fig. 2.

80 Fig. 12 is a sectional view taken on the line 12—12 of Fig. 2.

85 Fig. 13 is a curve in which the elevation of the various portions of a typical ramp are plotted against the travel distance thereon.

90 In heretofore existing structures of the ramp type which are provided with inclined ways or ramps extending between the various floors, and over which the vehicles utilizing the structure are adapted to be driven under their own power in order to pass from floor to floor, the construction has been such that 95 the vehicles must travel an undue distance in

100 passing from floor to floor, principally because of defects in the theory of design. Not only have the conventional constructions necessitated such excessive distance which the vehicle must travel, but as a result of such 105 constructions the ramps and aisle-ways connecting the same have consumed a greater amount of floor space than I have found necessary, and thereby the efficiency of the structure as a whole has been reduced. Furthermore, as far as I am aware, in existing structures of this type the vehicles in passing from 110 one floor to another over the ramps are caused, because of the construction of the ramps, to be racked in approaching or leaving a ramp. 115 This is caused by the fact that in most of such structures, the ramps are horizontal in a direction transverse to their line of travel and the vehicles enter the ramps at an angle thereto so that in certain positions the wheels on 120 the inside of the vehicle are lifted before the wheels on the outside which results in a twist being given to the vehicle frame with consequent racking of the body and accentuates the tendency of the car to overturn due to the 125 centrifugal force acting on the same. Furthermore, in structures of this type wherein the ramps are curved and are horizontal 130 transversely to the path of travel, the effect is to give the passengers of the vehicle traversing the ramps the uncomfortable feeling of being out of balance, due to the same uncompensated action of centrifugal force.

135 In the present invention a structure is provided in which are two series of oppositely inclined ramps, each ramp of which includes a relatively straight mid portion and curved end portions, the straight portions of the ramps of one series being preferably spaced from the straight portions of the ramps of 140 the other series a distance equal to the depth of two car stalls plus the width of an aisle or driveway extending between the stalls, and the end portions of the ramps are curved to 145 such a degree as to minimize, if not substantially eliminate, a pathway of substantial proportions between the end portions of cooperating ramps. Furthermore, the end portions of the ramps are banked as well as any portion of the floor or path that may connect 150 such end portions of cooperating ramps, so that a vehicle in passing from one ramp to another ramp along the pathway connecting the same is tilted inwardly towards the axis of the path of travel, the effect of which is to give the 155 passengers within the vehicle the comfortable feeling of always being in balance.

160 By curving the end portions of the ramps as described, very little, if any, floor space is consumed in passing from one ramp to 165 another so that substantially all the floor space consumed by the ramps and their connected paths is only that of the ramps themselves. In banking the ramps at their end portions I prefer to maintain the outer por- 170

tion of the path of travel at a super-elevation to the floor on any portion of the floor space that may constitute a connecting path between the curved end portion of the ramps. 5 Where conditions make it advisable, a parking space adjacent such superelevation on substantially the same level as the highest point thereof may be provided without presenting any unusual difficulties.

10 I also provide at each end of each ramp a curved pathway leading from each end portion of the ramp, such curved pathway leading away from such ramp in a direction opposite to the direction of travel of the vehicle on the corresponding curved portion of the ramp, and I connect such curved pathway with the corresponding curved portion 15 of the ramp by a path of travel so that vehicles may leave the ramp at such end portions when either going up or coming down the same, or may pass from the floor outside of the ramp directly onto the adjacent ramp, or pass such adjacent ramp and move directly onto the ramp most remote therefrom.

20 These curved pathways are also banked downwardly in the direction of the axes of the line of travel thereon in a manner corresponding to the banking of the curved portions of the ramps previously described.

25 As an illustration of the present invention I show in the accompanying drawings a garage structure which may be considered as having a plurality of horizontal floors 27, 28 and 29, which floors may be considered as having an extent commensurate with the ground area of the building. As shown diagrammatically in Fig. 1, two series of ramps 22 and 23 respectively connect the various floors 27, 28 and 29, the ramps 22 of one series, as viewed in Fig. 1, extending upwardly 30 from left to right and the series 23 extending upwardly right to left, as viewed in Fig. 1, the respective ramps of each series being in vertical alignment with each other. All alternate ramps of each series 22 and 23 cooperate with alternate ramps of the other series to form two continuous superimposed drive- 35 ways between the various floors, each driveway being adapted to handle vehicular traffic in one direction only, thereby providing entirely separate paths for up and down traffic. As indicated in Fig. 2, the series 22 and 23 of the ramps are separated from each other by a distance equal to the depth of the car stalls 24 and 25 plus the width of the aisleway 26. The view in Fig. 2 is broken away to show fragments of the three floors 27, 28 and 29 which may be considered as the third, fourth and fifth floors respectively 40 of a structure of the class described. One ramp of the series 22 is shown as connecting the third floor with the fourth floor, and one ramp of the series 23 is shown connecting the fourth floor with the fifth floor, the two ramps 45 being considered as devoted to upgoing traffic.

fic only so that the traffic thereon will be deemed to travel in a counterclockwise direction, as viewed in Fig. 2; while the traffic on the ramps immediately above and below those indicated will be devoted to downgoing traffic only moving in a clockwise direction. Obviously, upgoing traffic may use the lane which gives it a clockwise direction of travel and downgoing traffic the lane which gives it a counterclockwise direction, if desired. Each of the ramps comprises a straight side portion 30 and curved end portions 31 and 32 respectively. In order to illustrate two modifications of the present invention I have shown the curved portions 31 of each ramp as extending to a point midway between the straight portions 30 of each series 22 and 23 so that the curved portions 31 actually meet with each other at such mid point, while the curved portions 32 of each ramp stop short of such mid point and the adjacent ends thereof may be connected together by a pathway such as 33 which in reality forms no part of the ramp itself, in that vehicles passing over the same are neither elevated or depressed relative to the adjacent floor. To further illustrate the difference between these two modifications, it may be assumed that the outer edge of the path of travel of the portions 31 for each pair of cooperating opposed ramps have a common center of curvature at 34, and that the outer edge of the path of travel of each curved portion 32 has its own circular center as at 35, the centers 35 being spaced from each other. The portions 30, 31 and 32 cooperate to form a single ramp upon which a vehicle traveling the same is continuously either ascending or descending, while a vehicle on the portion 33 connecting the portions 32 neither ascends or descends. By making the distance between the opposed straight portions 30 of opposite ramps the distance described, the maximum use of the floor space therebetween for storage purposes is obtained, and by curving the ends of the ramps inwardly, as described, the minimum of floor space, which will otherwise be useful for storage space, is utilized for the ramps themselves and in passing from one ramp to another ramp.

It will be understood, of course, that in any particular construction where the present invention is employed, the ramps will preferably be constructed with the straight portions 30 having their ends curved as at 31, or as at 32, and not both the curved portions 31 and 32, as illustrated, except in those cases where the variation in the two curved ends, as illustrated, may be found beneficial for some reason or another. Should it be found desirable to employ the curved end portions 31 in preference to the curved end portions 32, the alternate ramps of one series will cooperate with the alternate ramps of the op-

posed series to provide a continuously ascending or descending ramp extending from the bottom floor of the structure to the top floor, but where it is found desirable to employ the end portions 32, there will be a break in the ascent or descent upon reaching the portion 33 connecting the opposed portions 32 at each floor.

The ascent or descent of the portions 30, 31 and 32 are shown diagrammatically in Fig. 4 which may be taken as a slightly enlarged diagrammatic developed section through the center line of the path of travel of the portions 30, 31 and 32. It will be noted that the portions 30 and 31 provide a continuous ascent or descent on the same, while the end portion of the portion 32 where it joins with the portion 33 is gradually merged into the horizontal to provide a smooth curve meeting the portion 33 to obviate the sharp break in ascent and descent found in so many of the existing conventional ramp structures.

In accordance with the present invention the portions 31 are banked downwardly towards the axis of the path of travel, starting from a minimum at or near the point of junction between the portions 31 and 30 to a maximum intermediate the portions 30, and where the curved portions 32 are employed, they are banked downwardly towards the axis of travel thereon from a minimum at or near the point of junction with the portions 30 to a maximum preferably at the point of junction with the portion 33, the portion 33 being banked also and preferably in accordance with the maximum banking of the portions 32. All points on the portions 31, 32 and 33 outwardly the inner edge of the path of travel of such portions are maintained at a superelevation with respect to the inner edge of the path of travel thereon.

Furthermore, the amount of superelevation of the portions 31, 32 and 33 increases in accordance with the distance away from the inner edge of the path of travel. This is best brought out in the graph shown in Fig. 13 which illustrates the elevations of the inside, intermediate and outside line of the travel lane plotted against the length of such lanes from the mid point of one of the straight portions 30 to the mid point of another straight portion 30 of a structure employing the curved end portions 32 connected together by the portion 33. This may be taken as a typical example of a structure employing the present invention. It will be noted from this graph that the elevation of the intermediate line of travel lane for the portions 32 and 33 is greater than that of the elevations on the inside line of the travel lane, while the elevations of the outside line of travel lane have a much greater value with respect to the intermediate line of travel lane than the intermediate line of travel lane has with respect to the inside line of travel lane. This graph also shows plainly the effect of the vertical

curve, introduced at points where there is a change of grade, in providing a smooth path of travel.

The effect of this banking, together with the use of vertical curves wherever there is a change of grade, is to eliminate racking of vehicles in ascending or descending the ramps, to provide a maximum of comfort for the passengers, to shorten the distance traveled in going from floor to floor, and to greatly facilitate the flow of traffic in and out of the structure, all of which are factors of the greatest importance in determining the commercial practicability of such a structure.

In the present invention I provide inner and outer abutments or railings 36 and 37 at the inner and outer edges of the path of travel along the straight portions 30 of each ramp and extending a short distance onto the curved portions 31 and 32. The floor between each series of ramps and between the end portions of the inner railings 36 is curved or warped either upwardly or downwardly according to the superelevation or subelevation of the adjacent ramp cooperating therewith, as the case may be, so as to merge into the corresponding end portions of the ramps as illustrated in Figs. 9, 10, 11 and 12, so that a vehicle in approaching the floor or leaving the space between the series 22 and 23 of the ramps on each floor may reach the floor from the ramp, or the ramp from the floor over a gradually curving surface, free from any abrupt angles.

Where conditions permit, which will usually be the case with a structure constructed in accordance with the present invention because of the relatively small area of ground surface enclosed between the two series of ramps, parking or storage areas on each floor outside of the path of travel on the ramps may be provided, and in Fig. 2 a number of variations in such storage areas are shown. In some instances it may be found advisable to form a storage area at the ends of the ramps, such as is indicated at 40 in Fig. 2, of a depth equal to the depth of one stall or more, in which case, a vehicle traveling on the ramps or connecting path may be driven directly into its stall on such storage area 40. In such a case, the outer line of travel lane on the portions 32 and 33 being at a superelevation with the corresponding floor, it may be desirable, as illustrated in Figs. 3 and 5, to maintain the area 40 at substantially the same elevation as the elevation of the outer line of travel lane, which thus establishes such portions 40 at a slight superelevation to the corresponding floor. Furthermore, in order to prevent any vehicle thus parked on the portion 40 from possibility of inadvertently rolling back into the travel lane, such portion 40 is preferably inclined downwardly away from the travel lane so

that the natural tendency will be for the vehicle to move away from the travel lane. Storage areas such as 41 and 42 separated by aisleways 43 may also be provided outside of the side portions of the ramps, as indicated in Fig. 2, and where conditions permit, these may be supplemented by additional storage spaces 44 and 45 separated by aisleways 46, as illustrated in Fig. 2. Where a greater area at the end of the ramps than that shown at 40 is obtainable, one or more storage areas such as 47 and 48 separated by an aisleway 49 may be provided, as illustrated in Fig. 2. In such case, the areas 47, 48 and 49 are preferably on the same level as the remainder of the floor level and suitable pathways leading to or from the adjacent superelevated portion of the ramp are provided for vehicles approaching a ramp or leaving the same. Such pathways may be as shown at 50, 51, 52 and 53 in the accompanying drawings. Each of these pathways preferably extends outwardly from each end of each straight portion 30 with approximately the same curvature in a horizontal plane as the corresponding portion 31 or 32, as the case may be, and each of these curved paths are preferably banked downwardly towards the axis of the path of travel thereon and merge at their ends into the level of the cooperating floor. It will be noted that by this construction a so-called "hump" will be made between adjacent outer edges of the path of travel of each of these curved paths and the corresponding curved portion of the ramp. I have indicated in the drawings by the numeral 54 the hump between the path 50 and the cooperating curved end 31 of the adjacent ramp and the remaining humps cooperating with the paths 51, 52 and 53 as 55, 56 and 57 respectively. These humps are rounded off at their edges so as to gradually merge with the cooperating curved portions 31 or 32 of the ramps and with the cooperating paths 50, 51, 52 or 53, so as to provide a smooth path of travel over the same in order that a vehicle on one side of the building may pass, for instance, from the floor or storage space on that side of the building onto the curved pathway 50 over the hump 54 onto the curved portions 31 between the corresponding ramps and onto the straight portion 30 of the ramp most remote from its original point of storage, or may pass into the aisleway 26 between the two series of ramps. This provides means whereby a vehicle passing from a floor up a ramp may easily reach the same from any point on the floor and it also provides means whereby any vehicle ascending or descending a ramp may pass directly to any point on any floor without interfering with the passage of other vehicles on the travel lane of the ramps. It will further be apparent, of course, that a vehicle traveling up any ramp may turn directly from the end of the ramp into

the aisleway 26 and there proceed to the opposite end of the aisleway and there run onto the particular ramp leading down from such floor reserved for the use of downgoing vehicles only.

In order to provide visibility for the drivers of the vehicles utilizing the ramps so that they may readily see another vehicle approaching, traveling on or leaving a ramp upon which the driver in question wishes to place his vehicle, I form the railings 36 at a height preferably not exceeding three feet from a point extending upwardly on each ramp from each floor to a point substantially midway the straight portion 30 of the corresponding ramp. This leaves relatively wide openings 59 between the railings and the floor above which permits the driver of a vehicle in approaching a floor from a ramp to see a relatively wide area of the floor on both sides of the ramp a material distance before reaching the level of the floor, and also permits a driver approaching a ramp from a floor to observe a vehicle approaching the floor on a ramp while the latter is still a considerable distance from the floor. The railings 36 and 37 above the mid point of the portions 30 are preferably extended up to the floor thereabove so that fire doors may be positioned at the midpoint of each of the straight portions 30 so that when closed they completely seal one floor from the adjacent floor.

Formal changes may be made in the specific embodiment of the invention described without departing from the spirit or substance of the broad invention, the scope of which is commensurate with the appended claims.

What I claim is:

1. In combination, a pair of substantially level superposed vertically spaced floors, a ramp extending between said floors comprising a straight portion and curved end portions, the inner edge of the path of travel of said curved end portions terminating at each floor in the plane thereof and the outer edge of the path of travel of said curved end portions terminating at each floor at a super-elevation with respect thereto, the floor adjacent to each of said ramp ends being warped to merge into said ramp ends.

2. In combination, a pair of substantially level superposed vertically spaced floors, a ramp extending between said floors comprising a straight portion and curved end portions, the inner edge of the path of travel of said curved end portions terminating at each floor in the plane thereof and the outer edge of the path of travel of said curved end portions terminating at each floor at a super-elevation with respect thereto, and a pathway at each floor merging into the corresponding said curved end portions at one

end and merging into the plane of the floor at the other end thereof.

3. In combination, a pair of substantially level superposed vertically spaced floors, a ramp extending between said floors comprising a straight portion and curved end portions, the inner edge of the path of travel of said curved end portions terminating at each floor in the plane thereof and the outer edge of the path of travel of said curved end portions terminating at each floor at a super-elevation with respect thereto, and a pathway at each floor merging into the corresponding of said curved end portions at one end and merging into the plane of the floor at the other end thereof, said pathway being banked downwardly towards the axis of the path of travel thereon.

4. In combination, a pair of substantially level superposed vertically spaced floors, a ramp extending between said floors comprising a straight portion and curved end portions, the inner edge of the path of travel of said curved end portions terminating at each floor in the plane thereof and the outer edge of the path of travel of said curved end portions terminating at each floor at a super-elevation with respect thereto, and a pathway at each floor merging into the corresponding of said curved end portions at one end and merging into the plane of the floor at the other end thereof, said pathway being banked downwardly towards the axis of the path of travel thereon from a maximum at said ramp to a minimum at the point where vehicles thereon debouch upon the corresponding floor.

5. In combination, a pair of substantially level superposed vertically spaced floors, a ramp extending between said floors comprising a straight portion and curved end portions, the inner edge of the path of travel of said curved end portions terminating at each floor in the plane thereof and the outer edge of the path of travel of said curved end portions terminating at each floor at a super-elevation with respect thereto, a pathway at each floor merging into the corresponding of said curved end portions at one end and merging into the plane of the floor at the other end thereof, and other pathways connecting each of the first mentioned pathways and the corresponding curved end portions of said ramp, the last mentioned pathways extending substantially perpendicular to said straight portion.

6. In combination, a pair of substantially level superposed vertically spaced floors, a ramp extending between said floors comprising a straight portion and curved end portions, the inner edge of the path of travel of said curved end portions terminating at each floor in the plane thereof and the outer edge of the path of travel of said curved end portions terminating at each floor at a super-elevation with respect thereto, a pathway at each floor merging into the corresponding of

said curved end portions at one end and merging into the plane of the floor at the other end thereof, and other pathways connecting each of the first mentioned pathways and the corresponding curved end portions of said ramp, the last mentioned pathways extending substantially perpendicular to said straight portion.

7. In a structure of the class described, in combination, a horizontal floor, a ramp extending upwardly from said floor, a ramp extending downwardly from said floor, each of said ramps comprising a straight portion connected with said floor by a curved end portion, said curved end portions terminating at said floor in adjacent relationship with respect to each other and each of said curved end portions being banked, the floor between said ramps being warped to merge into the adjacent end portions of said ramps in a smooth curve.

8. In a structure of the class described, in combination, a horizontal floor, a ramp extending upwardly from said floor, a ramp extending downwardly from said floor, said ramps comprising a straight portion connected with said floor by a curved end portion, said curved end portions terminating at said floor in adjacent relationship with respect to each other and each of said curved end portions being banked with a maximum degree of banking at their line of termination at said floor, and a pathway connecting the adjacent ends of cooperating ramps banked in accordance with the maximum banking of said ends, said pathway merging into said floor along an edge of said pathway.

9. In a structure of the class described, in combination, a plurality of floors, two series of oppositely inclined ramps connecting said floors, one ramp of each series connecting each pair of adjacent floors, each ramp comprising a straight portion and curved end portions, the curved end portion of a ramp of one series terminating adjacent the curved end portion of a cooperating ramp of the other series to provide two substantially continuous and independent inclined pathways between floors, said curved end portions being banked downwardly towards the axis of the path of travel thereon from a minimum adjacent said straight portions to a maximum therebetween, and said floors being warped to merge into the corresponding curved end portions of said ramps.

10. In a structure of the class described, in combination, a plurality of superposed horizontal floors, two series of oppositely inclined ramps connecting said floors, each ramp of each series connecting a pair of adjacent floors, and each ramp of each series comprising a straight central portion and curved end portions, the straight portions of each series of ramps being parallel in plan view with the straight portions of the other of said

series, and the curved end portions of each ramp of each series terminating at and merging into the floors connected thereby and adjacent to and in the direction of the path of travel on the curved end portions of the cooperating ramps of the other of said series, and curved pathways leading off of each of said ramps from the ends of each of said straight portions in a direction opposite to the direction of curvature of the corresponding curved end portion of said ramps and merging into the corresponding floors.

11. In a structure of the class described, in combination, a plurality of superposed horizontal floors, two series of oppositely inclined ramps connecting said floors, each ramp of each series connecting a pair of adjacent floors, and each ramp of each series comprising a straight central portion and curved end portion, the straight portions of each series of ramps being parallel in plan view with the straight portions of the other of said series, and the curved end portions of each ramp of each series terminating at and merging into the floors connected thereby and adjacent to and in the direction of the path of travel on the curved end portions of the cooperating ramps of the other of said series, and curved pathways leading off of each of said ramps from the ends of each of said straight portions in a direction opposite to the direction of curvature of the corresponding curved end portion of said ramps and merging into corresponding floors, and other pathways connecting each of said curved pathways with the corresponding curved end portion of each of said ramps.

12. In a structure of the class described, in combination, a horizontal floor, a ramp extending upwardly from said floor, a ramp extending downwardly from said floor, each of said ramps comprising a straight portion connected to said floor by a curved end portion, said curved end portions terminating at said floor in opposed and adjacent relationship with respect to each other, the inner edge of the path of travel of said curved end portions terminating at said floor in the plane thereof, the outer edge of the path of travel of said curved end portions terminating at said floor at a superelevation with respect thereto, and a pathway connecting said curved end portions, the inner edge of said pathway merging into said floor, and the outer edge of said pathway extending from ramp end to ramp end at a superelevation with respect to said floor.

HENRY L. WOOLFENDEN.
